UNITED STATES PATENT OFFICE.

ARTHUR BESSEY SMITH, OF EVANSTON, ILLINOIS, ASSIGNOR TO AUTOMATIC ELECTRIC COMPANY, OF CHICAGO, ILLINOIS, A CORPORATION OF ILLINOIS.

TRUNK CIRCUITS FOR AUTOMATIC TELEPHONE SYSTEMS.

Application filed September 18, 1919. Serial No. 324,264.

To all whom it may concern:

Be it known that I, ARTHUR BESSEY SMITH, a citizen of the United States of America, and a resident of Evanston, in the county of Cook and State of Illinois, have invented certain new and useful Improvements in Trunk Circuits for Automatic Telephone Systems, of which the following is a specification.

10 My invention relates in general to automatic trunk circuits, but more particularly to trunk circuits connecting more or less isolated or separated automatic exchanges, and has for its primary object the provision of 15 means for handling a special case having to do with the collection of tolls on incoming calls, although certain broad features may be found to be of utility for other purposes.

Fig. 1 is a layout of the relative position 20 of a group of exchanges in which my invention may be best illustrated.

Fig. 2 is a diagram of the selective switching mechanism which is used to illustrate the features of my invention.

25 Referring to Fig. 1 of the drawings, the reference characters A, B, and C represent three exchanges which may be located in three different towns. We will assume that the towns in which exchanges B and C are located are relatively close together, or these exchanges may be in the same town or city. At any rate, they are so situated that a flat rate for calling is in force for inter-exchange 30 as well as local calls. Exchange A however, is somewhat more distant and while calls from exchange A to exchange B may carry no extra charge, there will be a toll charge 35 for calls from exchange A to exchange C. Inter-exchange as well as local calls are es-

40 tablished automatically by the subscribers except that an operator may complete those calls which carry an extra toll charge. The trunking may be described briefly as follows: At exchange A selector switches are 45 provided as usual which are common to the subscribers and which are used during a preliminary stage in all connections, local or inter-exchange. Thus the selector S has access to local trunks and also to trunks extending to exchange B, one of which is shown in the drawing. This trunk line terminates at exchange B in a selector S' which 50 may be termed a trunk selector to distinguish it from the local selector S², which is similar to selector S at exchange A. Se-

lectors S' and S² have access in common to local trunks in exchange B and to interexchange trunks extending to exchange C. It will be seen now that subscribers in both exchanges have access to trunk lines extending to exchange C. Since there is no extra charge for calls between exchanges B and C such calls are preferably established automatically, and to this end each trunk line is provided with a branch at exchange C which 60 terminates in an automatic switch. But there is a charge for calls from exchange A to exchange C which makes it necessary to route such calls thru an operator who can make appropriate record thereof. In order 65 to take care of this latter class of calls a second branch is provided for each trunk line which extends to an operator's position. Referring again to the drawing it will be seen that the trunk extending from exchange B 70 to exchange C terminates at the latter point in a switching device X which is adapted to connect the trunk line to the branch extending to jack J, or to the branch extending to 75 the switch S³.

80 The object of my invention is, specifically, the provision of automatic means at exchange C which is able to differentiate between calls from exchange A and calls from exchange B, and which is effective to direct 85 calls from exchange A to an operator and calls from exchange B to automatic switches thru the medium of which the subscribers complete the desired connections. The precise manner in which this is accomplished 90 and the preferred embodiment of the invention will be described more in detail hereinafter, reference being had to the accompanying drawing.

95 In the drawing (Fig. 2), the reference characters 30 and 31 indicate the two line conductors of one of the trunk lines connecting exchanges B and C. This trunk line terminates at exchange B in the repeating coil R' thru the medium of which the trunk 100 conductors are inductively connected to conductors 8 and 9. These latter conductors terminate in multiple contact sets in the banks of local selectors such as selectors S², Fig. 1, and also extend to multiple contact 105 sets in the banks of trunk selector such as the selector S', Fig. 1. In the drawing there is shown one contact set, comprising contacts 2, 3, and 4, which is located in the bank of a local selector; and another contact set 110

comprising contacts 5, 6, and 7, which is located in the bank of a trunk selector. It is understood that while the line contacts are multiplied between the local and trunk selectors, the private or test contacts are not so multiplied. Thus the test contact 3 is multiplied to other local selectors but not to trunk selectors while similarly test contact 6 is multiplied only to other trunk 10 selectors.

At exchange C the repeating coil R^2 is provided thru the medium of which the trunk conductors 30 and 31 are inductively connected to conductors 32 and 33, which are 15 normally connected to branch conductors 44 and 45 extending to jack J'. The other branch comprises conductors 42 and 43 which extend to a selector switch which may be the selector S^3 , Fig. 1. This latter branch 20 is normally disconnected but may be substituted for the other branch by the operation of relay 37.

It is thought that the operation and functions of the various relays can best be explained by describing the operations incident to the establishment of several representative connections over the trunk circuit. Accordingly it will be assumed first that a calling subscriber in exchange B has established connection thru the medium of the selector S^2 with the bank contacts 2, 3, and 4 for the purpose of connecting via the trunk circuit with a subscriber in exchange C. Upon the completion of the connection to the bank contacts 2, 3, and 4, the line relay 13 is energized in the usual manner over the calling subscriber's loop and upon attracting its armature 15 closes an energizing circuit for the slow acting relay 14. This latter relay pulls up and closes the well known holding circuit back to the selector S^2 , which extends from ground G' by way of armature 16 and its working contact, winding of relay 20, and conductor 10 to bank contact 3, whence it continues by way of the test wiper of the switch thru a relay whose function it is to maintain the switch in operated position, and thence to the ungrounded pole of the battery. Current flow in the holding circuit serves to energize relay 20, which upon energizing, completes a control circuit over the trunk line to exchange C as follows; ground at G^2 , thru the battery B' , working contact of armature 22 and the said armature, armature 18 and its working contact, working contact of armature 17 and the said armature, conductor 19, right hand windings of repeating coil R' in parallel, trunk conductors 30 and 31 in parallel, left hand windings of repeating coil R^2 in parallel, conductor 51, and windings of polarized relays 46 and 47 in series to ground G^3 . Upon the completion of the above circuit the direction of

current flow is such that polarized relay 47 is able to operate its armature, but polarized relay 46 remains inoperative. Relay 47, upon operating, completes a circuit for the relay 36 which in turn closes a circuit for the slow acting relay 37. This relay, upon energizing, disconnects the conductors 32 and 33 from branch conductors 44 and 45 at armatures 40 and 41, respectively, and connects them instead to the branch conductors 42 and 43 which extend to a selector switch, assumed to be the selector S^3 , Fig. 1. Relay 36 has already closed at its armature 39 a normally open contact in conductor 42 and it will be seen that relays 36 and 37 have now completed a loop circuit including the right hand windings of repeating coil R^2 and which extends to the line relay of the selector. 85

Controlling impulses for operating the selector switch and subsequent switches, in exchange C are transmitted over the trunk line in the following manner: When the subscriber at exchange B operates his calling device a series of interruptions are produced in the line circuit, thereby causing a corresponding series of deenergizations of line relay 13. At each deenergization relay 13 breaks the control circuit extending to exchange C, thereby causing the polarized relay 47 to deenergize a like number of times. Since relay 47 controls the circuit of relay 36, this relay also deenergizes a plurality of times and thereby produces a series of interruptions in the circuit which extends over the branch conductors 42 and 43 to the selector switch. Subsequent operations of the calling device by the subscriber at exchange B will result in the operation of an additional switch or switches in exchange C whereby the connection will be completed to the desired line, all in the well known manner. 105

Having described briefly the establishment of a connection between a subscriber in exchange B and one in exchange C, I will now describe the operation when a subscriber in exchange A is calling. It will be assumed that the calling subscriber desires to obtain connection with a subscriber in exchange C and that he has extended his line through the medium of selectors S and S' to the trunk line terminal comprising bank contacts 5, 6, and 7. Upon the completion of the connection, line relay 13 is energized, followed by the energization of relay 14, which relay closes the holding circuit back to the selector S' the same as was described in the case of selector S^2 , except that now the relay 21 is included instead of relay 20. Upon energizing, relay 21 connects the battery B^2 in the control circuit extending over the two conductors of the trunk in parallel to exchange C, where it 110

includes the polarized relays 46 and 47. Batteries B' and B² have different poles adapted for connection to the control circuit, or in other words, they have opposite poles grounded. It follows therefore that whereas in the former case polarized relay 47 was operated, this relay corresponding to battery B', in the present case relay 47 remains inoperative, and relay 46 is operated. At its armature 48 relay 46 closes an energizing circuit for the visual signal V, which may be readily traced over the branch conductors 44 and 45 and the right hand windings of repeating coil R². Upon perceiving the signal the operator will respond by inserting the answering plug of one of her cord circuits (not shown) in jack J', and will thereafter proceed as is usual in such cases, making proper record of the call, and then completing it to the called line in any suitable manner.

The foregoing explanation is believed to be sufficient to enable the invention to be readily understood. It will be seen that I have devised a trunk circuit connecting two exchanges and accessible at one end to two different classes of subscribers, and having means at the other end whereby calls from one class of subscribers are automatically routed to an operator, and whereby calls from the other class of subscribers are automatically routed via automatic switches.

What I claim as my invention is:

1. In a telephone system, a trunk line, two classes of subscribers having access to said trunk line when calling, two outgoing branches of said trunk line, automatic selective means for routing calls from said trunk line via either of said branches, a pair of relays constituting said selective means, a controlling circuit for said relays, a pair of batteries each adapted to operate a particular one of said relays, and means controlled according to the class of a calling subscriber for connecting one or the other of said batteries in said circuit.
2. In a telephone system, an exchange comprising an operator's position and a plurality of automatic switches, subscribers' lines grouped at two outside points, means whereby subscribers in both groups can call said exchange automatically, and automatic means controlled by currents of different character for selectively switching such calls independent of control by the subscribers, whereby calls from one group of subscribers are directed to the operator and calls from the other group are directed to automatic switches.
3. In a telephone system, a trunk line having two branches at one end thereof, subscribers' lines grouped at two points, means whereby subscribers in both groups can connect with said trunk at the end opposite said branches and extend calls thereover, and automatic means controlled over two sides of said trunk line in parallel for selectively switching such calls independent of control by the subscribers, whereby calls from one group of subscribers are extended over one branch of said trunk line and calls from the other group are extended over the other branch.
4. In a telephone system, a trunk line, branches of said trunk line at one end thereof, one branch extending to an operator's position and the other branch terminating in an automatic switch, two selector switches having access to said trunk at the opposite end thereof, and means for always signalling the operator via one of said branches when the trunk is seized by a particular one of said selectors and for always operating said automatic switch when the trunk is seized by the other of said selectors, said means controlled by currents of different character.
5. In a telephone system, a trunk line having two branches at one end thereof and a simplex circuit superimposed thereon, one branch being normally connected and extending to an operator's position and the other branch being normally disconnected and terminating in an automatic switch, two selector switches having access to said trunk at the undivided end thereof, and automatic means controlled over said superimposed circuit for completing the connection to the operator via the said connected branch whenever the trunk is seized by a particular one of said selectors, and for connecting the said normally disconnected branch and for disconnecting the other branch whenever the trunk line is seized by the other of said selectors.
6. In a telephone system, a trunk line having two branches at one end thereof, two selector switches having access to said trunk at the other end, a circuit superimposed on the conductors of said trunk line and including at the divided end of the trunk two relays for controlling extensions of said trunk over its two branches, respectively, two separate batteries at the other end of said trunk for separately operating said relays, and means whereby each of said selectors when it seizes the trunk line includes a particular one of said batteries in the said circuit.
7. In a telephone system, a trunk line having two branches at one end thereof, two selector switches having access to said trunk at the other end, a ground return circuit superimposed on the conductors of said trunk line, two polarized relays included in said circuit at the divided end of said trunk for controlling the connection of said trunk with its two branches, respectively, two batteries at the other end of said trunk having opposite poles grounded, and means whereby each of said selectors when it seizes the

trunk line completes the said circuit through a particular one of said batteries to operate a particular one of said relays.

8. In a telephone system, an exchange comprising an operator's position and a plurality of automatic switches, second and third exchanges each having subscribers' lines terminating therein, a trunk line accessible to subscribers lines in the second exchange and extending to said third exchange, another trunk line accessible to calls coming over said first trunk and also to subscribers in said third exchange, the said second trunk constituting means whereby subscribers in either the said second or third exchanges can call the said first exchange, and automatic means for selectively switching such calls independent of control by the subscribers whereby calls from the second exchange are directed to an operator and whereby calls from the third exchange are directed to automatic switches.

9. In a telephone system, two classes of lines, a trunk, means for connecting any line with said trunk at the incoming end thereof, two branches of said trunk at the outgoing end, discriminating mechanism at the incoming end of said trunk sensitive to the class to which a connected line belongs, and switching mechanism at the distant end controlled over a talking conductor of said trunk by said discriminating mechanism for routing all calls from lines of one class via one of said branches and all calls from lines of the other class via the other of said branches.

10. In a telephone system, a trunk line having two branches at the incoming end, an automatic selector switch having access to the first branch only, a second automatic selector switch having access to the second

branch only, two branches at the outgoing end of said trunk line, means including said selectors for extending calls over said trunk line, and cooperating means at opposite ends of said trunk line for insuring that all calls reaching the trunk line by way of one selector will be routed away from said trunk line via a particular branch at the distant end and that all calls arriving by way of the other selector will be routed via the other branch at the distant end.

11. In a telephone system, a trunk line having two branches at one end thereof, automatic switching mechanism for connecting a calling line with said trunk line at the other end, a circuit including the two talking conductors of said trunk line in parallel, and switching means at the junction of said branches controlled automatically over said circuit responsive to the establishment of said connection for routing the call over a particular one of said branches.

12. In a telephone system, a trunk line having two branches at the incoming end and two corresponding branches at the outgoing end, automatic switches for extending calls over said trunk line, a circuit including the two talking conductors of said trunk line in parallel, and mechanism at the outgoing end of said trunk line controlled over said circuit from the incoming end for automatically and selectively switching said calls, said mechanism including means for routing each call away from the trunk over the outgoing branch corresponding to the incoming branch in use.

Signed at Chicago, Cook County, Illinois, this 13th day of September, 1919.

ARTHUR BESSEY SMITH.
